UNITED STATES PATENT OFFICE.

LEE STURGES, OF CHICAGO, ILLINOIS.

REINFORCED BREAST FOR SHEET-METAL RECEPACLES.

No. 905,950.

Specification of Letters Patent.

Patented Dec. 8, 1908.

Application filed April 24, 1908. Serial No. 428,968.

To all whom it may concern:

Be it known that I, LEE STURGES, a citizen of the United States, and a resident of the city of Chicago, Cook county, Illinois, have 5 invented certain new and useful Improvements in Reinforced Breasts for Sheet-Metal Receptacles; and I do hereby declare that the following is a full, clear, and exact description of the same, reference being had to 10 the accompanying drawings, and to the letters of reference marked thereon, which form a part of this specification.

Heretofore in the construction of cans for shipping and handling milk, much expense 15 has been occasioned as well as loss in injury or destruction of the cans owing to the empty cans being thrown into the car for return to the shipper and the breast portion of the can, or more particularly the somewhat spheric- 20 ally convex upper portion of the can being caved in or indented, or even broken by the rough treatment such receptacles receive. This in practice has been found to be one of the first points where such receptacles give 25 way, and prove defective, and various attempts have been made to strengthen the breast or top of the can sufficiently to withstand such rough treatment and to prolong the life of the can for the purpose of avoiding 30 also the frequent and expensive repairs occasioned by the structural weakness in this portion. Such devices, however, and expedients have proven ineffective and have failed to go into general use because of the consider- 35 able expense entailed by the constructions heretofore used for that purpose and because also, of sometimes rendering the can unsanitary by affording a receptacle for dirt.

The object of this invention is to afford a 40 can of the class described having a reinforced breast rigidly and permanently secured thereto and united therewith to afford a unitary construction and affording no open joints for bacterial culture or dirt.

It is a further object of the invention to 45 afford a reinforcement for the breast of the can adapted to be secured in place without riveting and not only to strengthen the breast of the can, but as well to afford a more rigid 50 and positive connection with the neck of the can to the end of preventing any structural failure between the breast and neck, or between the reinforcement and the breast, or of the reinforced breast and which, when the 55 completed structure is tinned, affords a can breast and top unitary in character.

The invention consists in the matters hereinafter described and more fully pointed out and defined in the appended claims.

As shown in the drawings: Figure 1 is a 60 side elevation of a metallic can embodying my invention. Fig. 2 is an enlarged fragmentary section of the same before seaming the neck in place and before tinning. Fig. 3 is a similar view taken after the neck seam is 65 closed and after tinning.

As shown in the drawings: A indicates the breast of a milk can of familiar form and which is rigidly united to the body a, of the can in the usual or any desired manner and 70 is provided above the junction of the body and breast with a bumper bead a', of half round iron or other structural form to afford a reinforcement. Said breast as shown, is somewhat spherically concaved on the inner 75 side and is provided with an aperture at its top to receive the end of the neck C, below the bead c. On said breast beside the lower end of the neck is a reinforcing concave shell A', of heavy gage and which is, as shown, 80 spherically concave, but with less radius than the breast, so that said reinforcing shell bears upon the periphery of the breast at a point intermediate the neck and the bumper bead reinforcement, and affords a slight 85 space between the breast and the reinforcing shell above the lower edge of the latter. When so assembled, and the internal flange or end c' of the neck is seamed, or rolled down, as shown in Fig. 3, said reinforcing 90 shell is pinched or pressed downwardly in close contact with the brace for practically its entire inner surface, thereby producing a very fine binding pressure for its entire circumference on its periphery on the breast. 95 The can so formed is then tinned both within and without, the molten tin flowing into the joints and drawing upwardly between the reinforcement and the breast, firmly cements or solders the reinforcement and the bead c, 100 and inner flange c' thereto, affording in effect a unitary structure and one in which no aperture or opening whatever between the reinforcement and breast or reinforcement, breast and neck is afforded for contamination. 105

The handles D, may be secured in any suitable manner upon the breast by riveting or otherwise and, of course, the reinforcement may extend to any desired point intermediate the neck and breast and may be of 110 any desired gage or thickness, and, if desired, may be secured in place by means of the handle

in addition to the soldering effect due to the tinning and the pinching effect due to the closing of the seam in the neck.

Of course, numerous details of construction may be varied. I therefore do not pur-
5 pose limiting this application for patent otherwise than necessitated by the prior art.

I claim as my invention:

- 10 1. In a device of the class described a re-
inforcing breast for can breasts embracing a
layer of sheet metal engaged to the breast at
the can neck and covering the breast to a
point intermediate the neck and body a bead
in the can neck and a flange integral with the
15 neck adapted to clamp the reinforcing breast
and can breast therebetween.
- 20 2. A reinforcing breast for can breasts em-
bracing a layer of sheet metal of different
curvature than the can breast affording a
space therebetween and clamped against the
breast at the neck and the reinforcing breast
sprung to conform to the curvature of the
can breast.
- 25 3. A reinforcing breast for can breasts em-
bracing a layer of sheet metal engaged to the
breast by the can neck and extending down
over and fitting to the breast and rigidly se-
cured thereto intermediate the neck and can
body.
- 30 4. A reinforcing breast for cans embracing
a concave disk of sheet metal of less radius
than the can breast and adapted to be sprung
inwardly and locked to the breast by the can
neck and extending down over and rigidly se-
cured to the breast by tinning.
- 35 5. In combination a can body, the spheric-
ally convex breast and the neck of a spheric-

ally concave reinforcing breast having less
radius than the can breast and engaged
thereto, such engagement serving to spring 40
the reinforcing breast into close bearing with
the can breast at the periphery of the former.

6. A spherically concave reinforcing breast
for can breasts embracing a layer of sheet
metal adapted to be engaged to the breast by 45
the neck of the can and extending down and
over and sprung into close fitting contact
with the breast and a metallic lining for the
reinforcing breast and can breast.

7. A can embracing a breast, a reinforcing 50
breast and a neck having a bead and a flange
for securing the can breast and reinforcing
breast rigidly together.

8. A can consisting of a body, a breast, a
reinforcing breast of different curvature than 55
the breast adapted to conform to the curva-
ture of the breast and a neck securing the in-
ner ends of the breast and reinforcing breast
together.

9. A can embracing a body, a breast se- 60
cured thereto, a reinforcing breast fitted
over the can breast, and a neck for the can
provided with a bead to engage on the outer
side of the reinforcing breast and protruding
into the can, said inwardly protruding end of 65
the neck flanged beneath the can breast.

In testimony whereof I have hereunto
subscribed my name in the presence of two
subscribing witnesses.

LEE STURGES.
